UNITED STATES PATENT OFFICE.

WILLIAM S. ROMIGH AND DANIEL ROMIGH, OF WICHITA, KANSAS.

FENCE-MAKING MACHINE.

SPECIFICATION forming part of Letters Patent No. 321,534, dated July 7, 1885.

Application filed August 6, 1884. (No model.)

To all whom it may concern:

Be it known that we, WILLIAM S. ROMIGH and DANIEL ROMIGH, citizens of the United States of America, residing at Wichita, in the county of Sedgwick and State of Kansas, have invented certain new and useful Improvements in Fence-Making Machines, of which the following is a specification, reference being had therein to the accompanying drawings.

10 This invention has reference to improvements in fence-machines, the same pertaining more especially to the wire-holding spools, and twisting-heads with intermediate hollow or tubular shafts, said invention having for 15 its object, among other things, to reduce friction, to prevent the possibility of the twisting of the wire in its passage from the spools to and through the tubes and from the latter to the twisting-heads, and to adapt the 20 feeding of the wires or stringers according to the thickness of the palings or pickets; and the invention consists of the combinations of parts and their construction, substantially as hereinafter fully set forth and claimed.

25 In the accompanying drawings, Figure 1 is a plan view of our improvement in fence-machines. Fig. 2 is a longitudinal section, and Fig. 3 is a transverse section through the wire spool or drum. Fig. 4 is an end elevation of our invention.

30 In carrying out our invention we mount or support the spool or drum A, around which the wires are coiled or wound (two wires generally being wound or coiled upon a spool) 35 upon a shaft, a, within a bracket-support, B, of rolled or wrought iron, preferably, whereby, with the shaft of the spool, which shaft may be a headed bolt-rod nutted or bolted to said bracket or support, said bracket or support, by its expansive property, acts as a 40 tension-spring to prevent the jamming of the spool. The bracket or support B for the spool-shaft a is in the nature of an oblong frame open at its longer sides, with its end bars or 45 arms provided with apertures or open-ended slots b, to receive and permit the removal, when necessary, of the spool-shaft. We next provide a tubular or hollow shaft, C—say about an inch in diameter—for the passage of 50 the wires to form the picket or paling stringers. The shaft C is provided at one end with

a flanged bar or plate, d, which is cast with a collar, d', fitted and fastened upon said end of shaft by a set screw or screws.

To the flange plate or bar d, which may be 55 provided upon its face, at the upper and lower longitudinal edges, with flanges e e, is bolted the longer closed side of the bracket or support B between said flanges e, which flanges serve to facilitate the adjustment to its 60 place upon said bar or plate d of the bracket or support B.

The use of the hollow slender tubular shaft (being, as before stated, about an inch in diameter) permits the use of light boxing or 65 bearings, and therefore greatly lessens friction and effects a great reduction in the expense and labor of putting up the machine of which the foregoing constitutes a part.

Across an aperture in the longer closed side 70 of the bracket or support B, said aperture being in alignment with the passage of the tubular or hollow shaft C, is disposed a wire rod, f, with its ends passed at right angles to itself through the casting B and the flange-plate e, 75 and nutted or bolted upon the outer side of said plate. This wire rod serves to prevent the possibility of the twisting of the wires in their passage from the spool to and through the tubular or hollow shaft, said wires being 80 passed one upon each side of said wire rod, the same thereby passing from the outer end of said shaft untwisted to the twisting-head. To the said outer end of the shaft C is connected the twisting-head D, said head being 85 provided or formed with rearwardly-projecting arms g, also cast or formed at their rear ends with a collar, h, which is detachably connected to said end of shaft by a set screw or screws. The twisting-head D is provided with two, 90 four, or a greater even number of apertures, i, for the passage through it of the wires, the parallel ones of said apertures being arranged at varied distances apart, in order to accommodate the feeding or applying of the wires 95 to pickets or palings of different thicknesses, and to allow them to be closely twisted thereon and intertwined. The wires may be grasped by pinchers as they emerge from the outer end of the shaft C, and be drawn the rest of the 100 distance in their passage through the twisting-head, and be thus passed through the re-

quired apertures of said head, after which, in practice, they are passed and connected to the reel of the machine to which these improvements may be applied.

5 By reference to Fig. 1 it will be seen that we support our twister upon two journals or bearings, C', and rotate the same by means of a sprocket-wheel, D'; but we do not restrict ourselves to any particular means for supporting and rotating our twister, as it is obvious that the same may be effected by any well-known means.

It will of course be understood that as many spools, holders or castings, shafts, and 15 twisting-heads are used as the capacity of the machine requires or will accommodate, and that all other necessary paraphernalia employed in a fence-machine will accompany the application of our invention.

20 Having thus fully described our invention, what we claim, and desire to secure by Letters Patent, is:

1. A twister for a fence-making machine, having the hollow shaft C, and secured thereto cross-plate d, having flanges e, and bracket 25 or support B, having open-ended slots b, for supporting the spool-shaft, substantially as shown and described.

2. In a fence-machine, the twisting-head shaft having the spool-supports provided with 30 a wire rod or guide disposed in a plane extending transversely through the passage of said shaft, substantially as and for the purpose set forth.

In testimony whereof we affix our signatures 35 in presence of two witnesses.

WILLIAM S. ROMIGH.
DANIEL ROMIGH.
